H. M. GILL ET AL

RECORDING DEVICE

Filed Nov. 3, 1925

UNITED STATES PATENT OFFICE.

HARRISON M. GILL AND HOWARD H. BELL, OF TAFT, CALIFORNIA.

RECORDING DEVICE.

Application filed November 3, 1925. Serial No. 66,594.

This invention relates to recording devices and more particularly to a recording device for use on self-propelled vehicles for indicating when the vehicle is last repaired or furnished with fuel, oil and the like.

An important object of the invention is to produce a device of this character very cheaply and at the same time provide a durable construction.

10 A further object of the invention is to provide a device of this character in which the record changes are very readily made and which may be supported from the instrument board or other convenient portion 15 of the vehicle.

These and other objects we attain by the construction shown in the accompanying drawing, wherein for the purpose of illustration is shown a preferred embodiment of our invention and wherein:—

Figure 1 is a perspective view of a portion of the dash of an automobile showing a register constructed in accordance with our invention applied thereto;

25 Figure 2 is a perspective view of the register as viewed from the rear;

Figure 3 is a vertical sectional view through the register;

30 Figure 4 is a perspective of one of the angle bars.

Referring now more particularly to the drawings, the numeral 10 indicates a rectangular face plate having projecting rearwardly therefrom at its edges flanges 11 so that a shallow casing having an open rear face is provided. Depending from the flange 11 at the upper end of the plate is a flange 12 confronting the rear face of the plate 10 and provided centrally with a keyhole slot 13 providing means whereby it may be readily engaged with and disengaged from a support 14 carried by the instrument board 15 of the vehicle upon which the device is preferably applied at a point immediately 45 adjacent the speedometer 16 carried by the instrument board.

Seated within the casing is a relatively thick support or backing sheet 17, this backing sheet being of the same length as the 50 interior length of the casing and having formed therein a plurality of vertically extending slots 18. Associated with the backing strip are a plurality of angle bars 19, each having one flange 20 thereof arranged 55 between the front face of the backing sheet 17 and the rear face of the plate 10 while

the second flange 21 thereof extends through an associated slot 18 and is of greater width than the thickness of the backing sheet so that the rear edge of this flange projects 60 beyond the rear face of the backing sheet. While of greater width than the thickness of the backing sheet, these flanges are of less width than the flanges 11 of the plate 10 so that they may be completely housed 65 within the casing. The front faces of the flanges 20 have vertically disposed series of numerals from nought to nine thereon and the plate 10 is provided with an opening 22 through which the numerals may be 70 observed. The slots 18 are really in the nature of slits and the backing sheet 17 is preferably formed of relatively thick material such as cardboard or the like having a frictional grip against the flange 21 at the 75 sides of the slots so that the angle bars 19 may be held in adjusted position. These angle bars themselves may be formed of relatively heavy paper, if so desired. It will be obvious that by detaching the casing, the 80 numerals can be changed to coincide with the setting of the odometer 16, at the time the vehicle is serviced and will provide an indication, in combination with this odometer, of the time at which further service is 85 necessary.

The front face of the plate 10 may have combined therewith a trough 23 forming an ash-tray and may have its upper front surface roughened, as indicated at 24, to 90 provide a surface upon which matches may be scratched. It will be obvious that a device of this character will be of great convenience to the motorist, providing, as it does, a permanent record of the last 95 servicing of the machine, which may be very cheaply produced and readily manipulated.

It will also be obvious that the construction hereinbefore set forth is obviously capable of a certain range of change and modification without materially departing from the spirit of our invention and we accordingly do not limit ourselves to such specific structure except as hereinafter claimed.

We claim:—

1. In a device of the character described, a casing having an open back and being relatively shallow from front to back, a backing sheet arranged within the casing and having vertical slits, angle bars each having one flange thereof disposed between the front casing wall and the front face of the 110

- backing strip and the second flange thereof disposed within a vertical slit of the backing sheet and projecting through the rear face thereof, the first named flanges of the 5 angle bars having vertically arranged indicia series, the front wall of the casing having an opening through which said indicia may be observed.
2. In a device of the character described, 10 a casing having an open back and being relatively shallow from front to back, a backing sheet arranged within the casing and having vertical slits, angle bars each having one flange thereof disposed between the 15 front casing wall and the front face of the backing strip and the second flange thereof disposed within a vertical slit of the backing sheet and projecting through the rear face thereof, the first named flanges of the 20 angle bars having vertically arranged indicia series, the front wall of the casing having an opening through which said indicia may be observed, said backing strip fitting closely between and being supported 25 from the upper and lower walls of the casing.

3. In a device of the character described, a casing having an open back and being relatively shallow from front to back, a backing sheet arranged within the casing 30 and having vertical slits, angle bars each having one flange thereof disposed between the front casing wall and the front face of the backing strip and the second flange thereof disposed within a vertical slit of 35 the backing sheet and projecting through the rear face thereof, the first named flanges of the angle bars having vertically arranged indicia series, the front wall of the casing having an opening through which said indicia 40 may be observed, said backing strip fitting closely between and being supported from the upper and lower walls of the casing, the upper wall of the casing having a depending flange at its rear edge and means 45 upon said flange for attaching the casing to a support.

In testimony whereof we hereunto affix our signatures.

HARRISON M. GILL.
HOWARD H. BELL.
